ENGINE STARTING APPARATUS

Lawrence C. Dermond, Rochester, N. Y., assignor
to General Motors Corporation, Detroit, Mich.,
a corporation of Delaware.

Application January 22, 1952, Serial No. 267,652.

13 Claims. (Cl. 290—38)

1

This invention relates to engine starting apparatus and particularly to the semi-automatic type of starting apparatus in which the control circuit therefor is closed normally to effect operation of the starting motor but in which closing of the control circuit is automatically prevented when the engine is self-operative.

A starting apparatus of this type is shown in the copending application of Paul L. Schneider, Serial No. 233,031, filed June 22, 1951, and the present invention is in the nature of an improvement on the device disclosed therein and includes various improved details of construction, particularly in the control switch which is effective to control operation of the apparatus. One of the features of the present invention is a movable contact member which is loose on its operating shaft so that the shaft makes a predetermined idle movement from its closed or open position before it picks up the contact. A further feature of improvement is the provision of a piston which is directly operated by engine suction to prevent the closing of the starter control circuit during operation of the engine under its own power and which is held in engagement with the movable contact by a spring so as to hold the contact against movement until positively moved by its operating shaft.

A still further feature of the invention is a means which enables a less amount of engine suction to hold the said piston in the position to which it is moved to prevent closing of the starter control circuit than is required to move it to such position.

Further objects and advantages of the present invention will be apparent from the following description, reference being had to the accompanying drawings wherein a preferred embodiment of the present invention is clearly shown.

In the drawings:

Fig. 1 is a diagrammatic view of a starting apparatus having a control switch constructed in accordance with the present invention.

Fig. 2 is a vertical section showing the control switch attached to the carburetor with which it is associated.

Fig. 3 is a section on the line 3—3 of Fig. 2.

In Fig. 1 the entire control circuit of a starting apparatus in which the control switch of the present invention is adapted to be used, is shown. In such figure, 20 designates a generator grounded at 21 and connected by a wire 22 with the current winding 23 of a reverse current relay 24. Winding 23 is connected with the frame 25 of relay 24, which frame supports a

leaf spring hinge 26 to which one end of the armature 27 is attached. Armature 27 carries a contact 28 engageable with its stationary contact 29 carried by bracket 30 connected by wire 31 with an ammeter 32 connected by wires 33 and 34 with the battery 35 grounded at 36. This completes the generator-to-battery circuit. A voltage coil 37 is connected with the relay frame 25 and is grounded at 38. The frame 25 supports a core 39 which is surrounded by the windings 23 and 37 although these windings are shown in the drawing as separated from the core 39. The relay contacts 28 and 29 are closed to complete the battery charging circuit by the magnetic action produced by current flowing through the voltage winding 37 after the generator has attained a certain voltage. When the contacts 28 and 29 are closed, current then flows through the winding 23 which then cooperates with winding 37 to hold the armature 27 in position to maintain the contact 28 in engagement with the contact 29. It is therefore apparent that the relay can be adjusted so that its contacts will not be separated due to the action of the spring hinge 26 until after the voltage of the generator has fallen substantially below that voltage required for the closing of the relay contacts 28 and 29.

The main engine cranking circuit comprises the battery 35, wire 34, switch contact 40, movable contact 41, switch contact 42, wire 43, starting motor 44 which is grounded at 45, and battery ground connection 36. The starting motor 44 operates the shaft 46 along which slides a sleeve 47 which is splined on the shaft 46 and which is operatively connected through a one-way or overrunning clutch 48 with a pinion 49 engageable with the engine flywheel gear 50. The sleeve 47 is surrounded by a grooved collar 51 which is slidable along the sleeve 47 but normally is held against a shoulder 52 at the left end of the sleeve 47 by a spring 53 interposed between the collar 51 and the clutch 48. The collar 51 is caused to move toward the right in the drawing by lever 54 pivotally mounted upon a shaft 55 and carrying at its lower end a pin 56 received by the groove of the collar 51. Movement of the lever 54 counterclockwise will cause the sleeve 47 to be moved toward the right and the pinion 49 to become engaged with the flywheel gear 50. The pinion 49 is withdrawn from the gear 50 by the operation of a spring 57 which surrounds the shaft 55 and bears at one end against a stationary stop 58 and at the other against a stop 59 carried by the lever 54.

The lever 54 is actuated and the switch 40, 41, 42 is closed by electromagnetic means which comprises a solenoid core 60 and a solenoid armature 61 which are surrounded by electromagnetic windings 62 and 63. The solenoid core 60 is provided with a central bore for receiving a horizontally slideable plunger or rod 64 on which the contact 41 is movably supported between two springs. The solenoid armature 61 is connected by a pin 74 with a link 75 which carries a stud 76 received by a slot 77 provided in the upper end of the lever 54.

When sufficient current passes through the windings 62 and 63, the armature 61 is caused to move toward the left in order to effect counter-clockwise movement of the lever 54 and the movement of the pinion 49 into mesh with the engine gear 50. This movement of the solenoid 61 also causes the rod 64 to move to the left carrying with it the switch contact 41 which is yieldingly pressed into engagement with the contacts 40 and 42. When this occurs, current will flow from the battery to the motor 44, thereby causing rotation of its armature shaft 46 and the pinion 49 driven thereby through the splined sleeve 47 and the overrunning clutch 48, thereby causing the fly-wheel gear 50 to rotate and the engine to be cranked for starting purposes. Should the engine fail to start and the pinion 49 fail to be withdrawn from the fly-wheel gear 50 by the action of the spring 57, it is possible to open the circuit of the starting motor by disconnecting the magnet coil windings 62 and 63 from the storage battery, the connections to which are to be described later. When the magnet coils 62 and 63 are deenergized, movement of the contact 41 away from the contacts 40 and 42 may take place due to the fact that the solenoid 61 may move toward the right slightly although the lever 54 may not be turned. This is possible due to the lost motion connection provided by the pin 76 and the slot 77 between the solenoid armature 61 and the lever 54.

Should the end faces of the teeth of the pinion 49 abut with the end faces of the gear 50 before meshing, it is possible to close the motor circuit in order that the pinion 49 may be rotated into meshing relation with the engine gear 50. This is possible due to the fact that the switch contacts 40, 41, 42 can be closed before the meshing of pinion 49 with gear 50 takes place. The solenoid armature 61 moves to close the motor switch and to move the pinion 49 toward the gear 50; but, after the pinion 49 collides with the gear 50, the spring 53 is compressed beyond its initial state of compression. Then when the motor shaft 46 turns to relieve the condition of gear tooth abutment, the spring 53 is released quickly to snap or jump the pinion 49 into engagement with the engine gear 50.

The circuit for connecting the magnet windings 62 and 63 with the storage battery 35 comprises the following circuit; battery 35, wire 34, contact 40, frame 31 of the starter control relay 80, leaf spring hinge 32, armature 83, contact 84, stationary contact 85, bracket 86, wire 87, winding 63, ground connection 88 and battery ground connection 36. The circuit of the other winding 62 includes the foregoing circuit as far as the bracket 86. From the bracket 86 a wire 90 leads out to connect with the coil 62 which is connected by wire 90a with the contact 42. The circuit of coil 62 is completed to the battery through the motor 44 and ground connections 45 and 36. It is apparent that when the contacts 84 and 85 of the

starter relay 80 are closed, current will flow through both windings 62 and 63 to cause the solenoid 61 to move toward the left in order to shift the pinion 49 into engagement with the gear 50 and to close the switch contacts 40, 41, 42. When the motor switch closes, the winding 62 will be short circuited. The winding 62 is made preferably of relatively coarse wire whereas the winding 63 is constructed of relatively fine wire. Both windings 62 and 63 are required to draw the armature 61 across to the core 60 but, when this relation has been established, the one winding 63 is all that is required to maintain this relationship. Therefore, the winding 62 which consumes the greater amount of current is short circuited so that the starting motor will have adequate current for cranking the engine.

The operation of the relay 80 is controlled in part by the ignition switch 93 and a switch 94 which are in series, the switch 94 being closed by the carburetor throttle to effect starting and prevented from closing during engine operation by action of engine suction. To this end, one terminal 95 of the ignition switch is connected to the wire 31 leading to the battery, by a wire 96, while another terminal 97 is connected by wire 98 to one of the contacts of the switch 94, while another contact of this switch is connected by wire 99 to the winding 100 of the relay 80 and this winding is connected by wire 101 with bracket 102 supporting contact 103 adapted to engage contact 104 carried by bracket 27 of the cut-out relay and connected by wire 105 with the ground connection 38. The movable contact 106 of the ignition switch will engage terminals 95 and 97 when the switch is closed and obviously when the contacts 103 and 104 are in engagement with the ignition switch and switch 94 closed, the winding 100 will be energized. This will cause engagement of contacts 84 and 85 and operation of the main magnet to close the starting motor circuit. When contacts 103 and 104 are separated by action of the generator, the winding 80 cannot be energized and the starting motor circuit cannot be closed.

The control circuit above-described is just the same as shown in the aforementioned Schneider application, but the switch 94 is of quite different construction from that shown in such application. The switch 94, as disclosed herein, includes a housing 110 which may be secured in any desirable way to a boss 111 extending from the throttle outlet casting 112. As shown, the boss has a recess formed thereon into which an annular boss 113 extending from housing 110, fits. In the boss 113 is a bushing 114 and extending through the bushing is the shaft 115 on which the throttle valve 116 is secured. A removable plate of suitable insulating material 117 closes one end of the housing 110 and when removed permits access to the interior of the housing 110.

Suitably secured in the plate 117 are binding posts 118 and 119 connected respectively with the wires 98 and 99 and connected to these binding posts are contacts 120 and 121, both of which must be engaged by a movable contact 122 in order to effect energization of the starting motor. This contact is a strip of metal suitably attached to and supported by a block of insulating material 123 rotatably mounted on a reduced portion 124 of the throttle shaft, and having an arcuate peripheral surface 125 at a greater distance from the axis of shaft 115 than is the contact 122, such surface being normally engaged by the contact 120 as shown in the drawings.

The closing of the control circuit is effected by counterclockwise rotation of the block 123, as seen in Fig. 2, to permit the contact 120, which is biased towards the left, to move off the surface 125 and snap into engagement with the contact 122, which always engages contact 121 in any position of the block 123. Rotation of the block 123 to effect both closing and opening of the control switch is accomplished by a pin 126, secured in position in a transverse opening in the throttle shaft in any suitable way and this pin engages lugs 127 and 128 projecting from block 123 as the throttle shaft is rotated, to rotate the block 123 in opposite directions. These lugs may be integral with the block as shown, or metal pins suitably secured in the block.

Formed in the housing 110 is a cylinder 130 in which slides a piston 131 normally held in the position shown in the drawings by a spring 132, so that a lug 133 projecting from the piston engages the surface of the block 123. The piston is preferably formed of Bakelite or similar material but a metal piston may be used. Retained in position in the upper end of cylinder 130 by a suitable clamping ring 134 is a sealing washer of copper or other suitable material, which is engaged by the end surface 136 of the piston when the latter is moved by engine suction against the force of the spring. Engagement of surface 136 with the washer 135 effects a seal so that when the piston is in its housed position and engaging the seal washer, less suction is required to hold the washer in such position than is required to move it thereto. The end surface 136 is cut away at 137 to provide a space in which the retaining ring 134 is received when the piston engages the seal washer.

Normally, the contact 120 is in the position shown in the drawings, but when the switch is closed, such contact moves to the left until the bent portion thereof, 140, engages contact 122. When this takes place, a toe 141 at the top of contact 120 projects through an opening 142 in the wall of cylinder 130, into a channel 143 in the peripheral surface of piston 131. The channel 143 is of unequal depth at different parts thereof so that a shoulder 144 is formed. When the parts are in the position shown in the drawings, the piston may move freely in response to effect of engine suction, but when the switch 94 is closed and the toe 141 extends into channel 142, the upward movement of the piston 131 is limited by engagement with the toe 141.

A suction passage 150 is formed in the upper closed end of the housing 110 and the passage 150 may be connected in any suitable way with a passage 151 in the wall of the carburetor casting 112, which connects through bore 152 with the carburetor outlet passage 153, posterior to the throttle. The form of the suction passage is not material, but as illustrated, passage 151 connects with an annular channel 154 formed in the wall of a threaded bore 155 in the carburetor casting 112. A reversely threaded coupling member 156 may be screwed into the bore 155 and a similar bore 157 in the housing 110, and an opening 158 in the coupling member connects with the channel 154 in any position of the coupling member and the coupling member is also a means to attach the housing 110 to the carburetor casting. It will be understood, however, that the suction connection is no part of the present invention and the passage 150 may be connected to the carburetor intake by any means which is deemed satisfactory.

The housing 110 is preferably of die cast metal and is provided with an opening 160 to admit air in which is positioned a very fine meshed screen 161 to prevent, as far as possible the admission of dirt.

As already indicated, the switch is closed by counterclockwise rotation of the block 123 which permits the bent portion 140 of contact 120 to move into engagement with contact 122. Opening of the switch is also manual and is effected by a reverse or clockwise rotation of block 123. When this takes place, a cam shoulder 162 engages the portion 140 of contact 120 and moves such contact to the right so that 140 rides on the surface 125 as indicated in the drawings. This cam surface is made as abrupt as possible without causing a binding action between such surface and the part 140 because it is desirable to close the switch with a snap action and it is important that the cam does not have a gradual enough slope to cause the movement of the switch contact to closed position to be retarded by the gradual slope of the cam.

In the drawings, the parts are shown in the normal position with closed throttle. To close the switch, the throttle is moved toward open position and the pin 126 moves toward the left until it engages lug 127 before the block 123 is moved, the pressure of piston 131 and contact 120 preventing movement of the block. Upon engagement of the pin and lug, a very slight additional opening of the throttle moves the block enough to permit movement of the part 140 into engagement with contact 122 to close the switch, and the throttle may then move on to open position while the switch remains closed. The lug 127 is so positioned that the throttle makes that amount of opening movement found to be most desirable before engagement of the pin 126 with the lug and movement of the block to switch closing position. The throttle can then move on further toward open position, if necessary, without opening the switch.

When the engine starts, the suction pulls the piston 131 upwardly until shoulder 144 engages toe 141 and it is stopped in that position until the switch is opened manually to disengage the toe from said shoulder. To open the switch, the throttle is closed and is moved toward closed position without moving block 123 at all until pin 126 engages lug 128, after which continued closing movement of the throttle moves the parts to the position shown in the drawings, opening the switch and permitting the piston to be lifted until surface 136 engages the seal washer 135. When the piston is in this position, opening of the throttle will not effect closing of the switch because the toe 141 engages the surface 163 of the shallow part of channel 143 and the part 140 cannot move far enough to engage contact 122.

When the piston is lifted as described, the drop in suction occasioned by continued opening of the throttle will not cause the piston to drop and permit closing of the switch, because of the previously described action of the sealing washer and because of the fact that the toe 141 exerts so much pressure against the side of the piston that it will not be overcome by the weight of the piston and spring 132. The switch, therefore, will not close during operation of the engine under its own power.

While the embodiment of the present invention as herein disclosed constitutes a preferred form, it is to be understood that other forms might be adopted.

What is claimed is as follows:

1. In a starting apparatus for internal combustion engines having a starting motor, a current source and a circuit for connecting said starting motor with the current source; a control switch for controlling said circuit having a switch operating member movable to different positions to effect closing and opening of said switch, manual means for operating said member and operable to move said member to effect either closing or opening of said switch means permitting a predetermined movement of said manual means before said switch operating member is moved, a member movable during self-operation of the engine to a position to prevent closing of said switch, means operative to prevent movement of said member to its effective position while said switch is closed, and means operable to release said member to permit operation thereof when said switch closing member is moved to its normal switch opening position.

2. In a starting apparatus for internal combustion engines having a starting motor, a current source and a circuit for connecting said starting motor with the current source; a control switch for controlling said circuit having a switch operating member movable to different positions to effect closing and opening of said switch, manual means for operating said member and operable to move said member to effect either closing or opening of said switch only after a predetermined movement of said manual means, a member movable during self-operation of the engine to a position to prevent closing of said switch, resilient means normally holding said last-named member in engagement with said switch operating member to prevent movement of the latter during part of the movement of said manual operating means.

3. In a starting apparatus for internal combustion engines having a starting motor, a current source, a control switch effective when closed to cause the starting motor to be connected with said current source and when opened to interrupt such connection, a carburetor throttle valve for controlling the amount of combustible mixture supplied to the engine and an operating shaft therefor, a member operable by said shaft to effect closing of said control switch, and means permitting a predetermined closing movement of said throttle shaft before said member is moved thereby, a member movable to a position to prevent closing of said switch during self operation of the engine, means for preventing movement of said member while said switch is closed, means for rendering said last-named means ineffective when the switch is opened, and means operable to effect opening of the switch when the throttle is moved to closed position.

4. In a starting apparatus for internal combustion engines having a starting motor, a current source, a control switch effective when closed to cause the starting motor to be connected with said current source and when opened to interrupt such connection, a carburetor throttle valve for controlling the amount of combustible mixture supplied to the engine and an operating shaft therefor, means operable by said shaft only after a predetermined movement thereof to effect closing of said control switch, a member movable to a position to prevent closing of said switch during self operation of the engine, means for preventing movement of said member while said switch is closed, means for rendering said last-named means ineffective when the switch is

opened, means operable to effect opening of the switch when the throttle is moved to closed position, and resilient means holding said member in engagement with the means operable by the throttle shaft to close the switch, so as to oppose movement of said means by the said throttle shaft.

5. In a starting apparatus for internal combustion engines having a starting motor, a current source, a control switch effective when closed to cause the starting motor to be connected with said current source and when opened to interrupt such connection, a carburetor throttle valve for controlling the amount of combustible mixture supplied to the engine and an operating shaft therefor, means operable by said shaft only after a predetermined movement thereof to effect closing of said control switch, a member movable to a position to prevent closing of said switch during self operation of the engine, means for preventing movement of said member while said switch is closed, means for rendering said last-named means ineffective when the switch is opened, means operable to effect opening of the switch when the throttle is moved to closed position, resilient means holding said member in engagement with the means operable by the throttle shaft to close the switch, so as to oppose movement of said means by the said throttle shaft, and means whereby engine suction moves said member to a position to render said resilient means ineffective when the engine is operating under its own power.

6. In a starting apparatus for internal combustion engines having a starting motor, a current source, a control switch effective when closed to cause the starting motor to be connected with said current source and when opened to interrupt such connection, a carburetor throttle valve for controlling the amount of combustible mixture supplied to the engine and an operating shaft therefor, means movable by said shaft as the throttle is opened to effect closing of said control switch and movable by said shaft as the throttle is closed to effect opening of the control switch, an operating connection between the throttle shaft and said movable means including a lost motion device whereby said means is effective to close the switch only after throttle has made a predetermined opening movement, and means yieldingly opposing movement of said movable means by the throttle shaft.

7. In a starting apparatus for internal combustion engines having a starting motor, a current source, a control switch effective when closed to cause the starting motor to be connected with said current source and when opened to interrupt such connection, a carburetor throttle valve for controlling the amount of combustible mixture supplied to the engine and an operating shaft therefor, a switch operating member rotatably supported by said throttle shaft, means effective after a predetermined opening movement of the throttle to connect the said member to said throttle shaft for rotation therewith so as to effect closing of the switch after the throttle has made a predetermined opening movement, a member normally engaging the surface of said switch operating member and acting as a brake to oppose movement of said member with the throttle shaft, and spring means exerting a predetermined pressure on said member.

8. In a starting apparatus for internal combustion engines having a starting motor, a cur-

rent source, a control switch effective when closed to cause the starting motor to be connected with said current source and when opened to interrupt such connection, a carburetor throttle valve for controlling the amount of combustible mixture supplied to the engine and an operating shaft therefor, a switch operating member rotatably supported by said throttle shaft, means effective after a predetermined opening movement of the throttle to connect the said member to said throttle shaft for rotation therewith so as to effect closing of the switch after the throttle has made a predetermined opening movement, a suction operated member movable to a position to prevent closing of said switch when the engine is operating under its own power, and resilient means normally holding said last-named member in engagement with said switch operating member to oppose movement of the switch operating member by the throttle shaft.

9. In a starting apparatus for internal combustion engines having a starting motor, a current source, a control switch effective when closed to cause the starting motor to be connected with said current source and when opened to interrupt such connection, a carburetor throttle valve for controlling the amount of combustible mixture supplied to the engine and an operating shaft therefor, a switch operating member rotatably mounted on the throttle shaft and having a lug projecting therefrom, and an operating member projecting from the throttle shaft and adapted to engage said lug and move the switch operating member to a position to close the switch after the throttle has made a predetermined opening movement.

10. In a starting apparatus for internal combustion engines having a starting motor, a current source, a control switch effective when closed to cause the starting motor to be connected with said current source and when opened to interrupt such connection, a carburetor throttle valve for controlling the amount of combustible mixture supplied to the engine and an operating shaft therefor, a switch operating member rotatably mounted on the throttle shaft and having a lug projecting therefrom, an operating member projecting from the throttle shaft and adapted to engage said lug and move the switch operating member to a position to close the switch after the throttle has made a predetermined opening movement, and resiliently operated means normally engaging said switch operating member and effective to hold said member against movement before engagement of said lug by the operating member.

11. In a starting apparatus for internal combustion engines having a starting motor, a current source, a control switch effective when closed to cause the starting motor to be connected with said current source and when opened to interrupt such connection, a carburetor throttle valve for controlling the amount of combustible mixture supplied to the engine and an operating shaft therefor, a switch operating member rotatably mounted on the throttle shaft and having a pair of spaced lugs projecting therefrom, an operating member extending from the throttle

shaft to a position between said lugs, said member being operable to engage one of said lugs and move the switch operating member to switch closing position only after the predetermined opening movement of the throttle and operable to engage the other lug only after a predetermined closing movement of the throttle from an open position.

12. In a starting apparatus for internal combustion engines having a starting motor, a current source and a circuit for connecting said starting motor with the current source, a control switch for controlling the opening and closing of said circuit and including a plurality of contacts and a switch operating member movable to different positions to effect closing and opening of said switch, manually operated means for actuating said member and effective to move said member to either switch closing or switch opening position, a cylinder having an opening therein through which a part of one of said switch contacts projects when the switch is closed, means for communicating the engine suction to said cylinder, a piston slideable in said cylinder and movable by engine suction when the engine is self-operative to a position where a surface on said piston is engaged by that part of said contact which extends through the cylinder opening and movement of the contact to switch closing position is prevented.

13. In a starting apparatus for internal combustion engines having a starting motor, a current source and a circuit for connecting said starting motor with the current source, a control switch for controlling the opening and closing of said circuit and including a plurality of contacts and a switch operating member movable to different positions to effect closing and opening of said switch, manually operated means for actuating said member and effective to move said member to either switch closing or switch opening position, a cylinder to which the engine suction is communicated and having a sealing washer positioned at one end of said cylinder, a piston slideable in said cylinder and movable by engine suction when the engine is self-operative, to a position where closing of the switch is prevented by the piston and in which one end of the piston engages the sealing washer, whereby the piston is held in position to prevent closing of the switch by a force less than that required to move it to such position.
